UNITED STATES PATENT OFFICE.

JOHN WARREN WATSON, OF WAYNE, AND ROBERT F. NOWALK, OF PHILADELPHIA, PENNSYLVANIA, ASSIGNEES TO JOHN WARREN WATSON COMPANY, OF PHILADELPHIA, PENNSYLVANIA, A CORPORATION OF PENNSYLVANIA.

DESIGN FOR A SHOCK-ABSORBER CASING.

Application filed May 11, 1928. Serial No. 26,643. Term of patent 14 years.

To all whom it may concern:

Be it known that we, JOHN WARREN WATSON and ROBERT F. NOWALK, citizens of the United States, residing, respectively, in Wayne, Delaware County, Pennsylvania, and Philadelphia, Pennsylvania, have invented a new, original, and ornamental Design for Shock-Absorber Casing, of which the following is a specification, reference being had to the accompanying drawing, forming part thereof, in which:

Figure 1 is a face view of a shock absorber casing made in accordance with our invention, and

Fig. 2 is a side view.

We claim:

The ornamental design for a shock absorber casing, as shown.

JOHN WARREN WATSON.
ROBERT F. NOWALK.
